UNITED STATES PATENT OFFICE.

WILLIAM CHARLES HOPEWELL, OF DRAYCOTT, ENGLAND.

TWIST LACE AND IN THE METHOD OF MAKING THE SAME.

Application filed September 14, 1922. Serial No. 588,181.

To all whom it may concern:

Be it known that I, WILLIAM CHARLES HOPEWELL, a subject of the King of Great Britain, residing at Victoria Mills, Draycott, in the county of Derby, in England, have invented Improvements in Twist Lace and in the Methods of Making the Same, of which the following is a specification.

This invention relates to improvements in twist lace and in the method of making the same, and has particular, although not exclusive, reference to the production of fabrics adapted for use in the manufacture of gas mantles and the like.

15 The principal object of the invention is to produce a fabric of the type referred to which presents two distinct plies or webs and which is adapted to withstand a longitudinal strain.

20 A further object of the invention is to produce simultaneously on one and the same machine two of such fabrics independently, or alternatively to produce such fabrics in tubular formation.

25 According to this invention, and for the production of only one fabric, the machine is fitted with four sets of warp or steel bars.

The threads carried by the first two sets of bars, which are superior to (i. e. in front of) the last two sets of bars, may be conveniently termed loop threads. The threads carried by the set of bars next to said two sets of bars may be conveniently termed cross threads, and the threads carried by the set 35 of bars which is inferior to (i. e. at the back of) the aforementioned sets of bars may conveniently be termed pillar threads.

The principal feature of this invention consists in producing a fabric on twist lace 40 machines which is composed of or presents two distinct webs, one of said webs being produced by so actuating the loop threads that each loop thread always twists with one and the same bobbin thread, adjacent loop 45 threads twisting with adjacent bobbin threads and the loop threads crossing or twisting with one another intermediate the bobbins with which they respectively twist.

A further feature of this invention consists in the production of the second web of 50 said fabric by means of cross threads which do not twist with the bobbin threads, but are always laid under or are always laid over the bobbin threads and tied thereto by 55 pillar threads, each of such latter threads

twisting with the same bobbin thread at each motion of the machine.

In the production of a fabric according to this invention adjacent loop threads are carried by independent adjacent sets of bars, such two sets of bars as previously stated being the most superior i. e. if a front fabric is being produced. If a back fabric is being produced then the bars carrying the loop threads would appear as the most superior 60 from the back of the machine. Shogging of the warp bars is effected in any usual and convenient manner customary to twist lace machines and on every fourth motion the two sets of bars carrying the loop threads 65 are shogged simultaneously in the same direction over two gaits first in one direction and then in the other direction. In the two intermediate motions one of such sets stands, that is to say, runs parallel with the bobbin 70 threads while the other set is shogged one gait at each motion first in one direction and then in the opposite direction and each set alternately rests while the other set is so shogged. Accordingly each loop thread 75 always twists with one and the same bobbin thread.

The set of bars carrying the cross threads is shogged two gaits first in one direction and then in the opposite direction every 80 other motion of the machine so that when such bars are shogged the carriages are always in the same position relatively thereto i. e. the carriages are either always in the front combs or are always in the back 85 combs. The pillar threads are shogged one gait every motion first in one direction and then in the other direction.

“One motion” may be expressed as the time taken for the carriages to swing 90 through from one set of combs to the opposite set of combs as is well understood in the art.

It will be appreciated that by reason of producing a fabric in the above manner 100 equal and opposite lateral forces are exerted on each bobbin so that the pillars remain vertical and further the cross threads strengthen the fabric without distorting said pillars.

In order that this invention may be more readily understood reference will now be made to the accompanying drawings wherein:

Fig. 1 is a diagrammatic view showing 110

how the threads are laid for the production of a front fabric according to this invention.

Fig. 2 is a diagrammatic view showing how the threads are laid for the production of a back fabric according to this invention.

Fig. 3 is a diagrammatic view illustrating how the threads are laid for the purpose of joining a back and front fabric or for the purpose of forming a tubular fabric.

Fig. 4 illustrates a front fabric woven in accordance with this invention.

Fig. 5 is a cross-section view of the fabric taken approximately on the line 5—5 of Fig. 4.

Referring to Fig. 1, the loop warp threads are represented at 1 and 2, loop threads 1 being in front of loop threads 2. The cross warp threads are represented at 3 and the pillar threads which are behind all of the aforementioned threads are represented at 4. The bobbin threads which are woven into the front fabric are represented at f , f' , f'' , etc. and the bobbin threads which are woven into the back fabric are represented at b , b' , b'' , etc. It will be noticed that each front bobbin thread is intermediate two back bobbin threads and each back bobbin is intermediate two front bobbins. That is to say, the bobbin threads in each fabric, both back and front, are spaced two gaits apart.

Further it will be appreciated that if it is desired to produce only a front fabric the back bobbin threads in Fig. 1 will be dispensed with and in this case the front bobbins could be spaced two gaits apart as shown or could be spaced one gait apart and the movements of the other threads modified to correspond.

Following the motions of the threads as shown in Fig. 1 it will be seen that each loop thread 2 twists twice with one bobbin thread f' while the loop threads 1 stand untwisted, that is, they run parallel with the bobbin thread. All of the loop threads are then shogged two gaits to the left (i. e. two gaits of the front fabric or web) and each loop thread 1 twists twice with one bobbin thread f while the loop threads 2 stand untwisted.

All the loop threads are then shogged two gaits to the right to their starting position and the cycle of movements of the loop threads is completed. This cycle of movements is continued throughout the production of the fabric. Each cross thread 3 is shogged two gaits first in one direction and then in the other direction, such shogging being simultaneous with and in the opposite direction from the shogging of the loop threads on the motions when all of such latter threads are shogged two gaits.

The cross threads do not twist with the bobbin threads f , f' but are tied to the adjacent bobbin threads which they cross by the pillar warp threads 4. Each pillar warp

thread twists continuously with one and the same bobbin thread i. e. each pillar thread is shogged one gait first in one direction and then in the opposite direction on each motion. The cross threads are under the bobbin threads f , f' on each motion and although such threads are above the pillar threads 4, yet by reason of such latter threads continuously twisting with the bobbin threads the cross threads are tied to the bobbin threads.

It will be noticed from Fig. 1 that all the back bobbin threads b , b' , b'' , etc. are behind all the other threads since these bobbin threads do not constitute part of the front fabric. The manner in which the back fabric is produced is represented at Fig. 2, the reference numerals 1^a, 2^a, 3^a and 4^a in this figure respectively corresponding to the reference numerals 1, 2, 3 and 4 shown in Fig. 1.

It will be appreciated however that since the back fabric is produced on the back of the machine the superiority of the threads 1^a, 2^a, 3^a and 4^a will be the reverse of that of the threads 1, 2, 3 and 4 of the front fabric.

For further elucidating this point it may be stated that the representation of the fabric in Fig. 2 is as seen from the front of the machine, but were this fabric to be represented as seen from the back of the machine the representation would be substantially the same as that shown in Fig. 1.

The movements of the loop threads 1^a and 2^a are substantially the same as the movements of the threads 1 and 2. The movements of the threads 3^a and 4^a are similarly substantially the same as the movements of the threads 3 and 4 respectively.

It will again be seen that the cross threads 3^a do not twist with the bobbin threads b , b' but always pass over such threads and are tied to the adjacent bobbin threads over which they cross by the most superior threads 4^a which latter threads are shogged first in one direction and then in the other, each pillar thread always twisting with one and the same bobbin at each motion.

The front bobbin threads f , f' , in Fig. 2 are shown in front of all the other threads. If only a back fabric were being produced such threads would not be shown but they are represented here for the purpose of assisting to show the relative disposition of all the threads when a front and back fabric are being produced.

In Fig. 1 is represented in dotted lines a portion of the back fabric being woven on to the bobbin threads b' , b'' , for the purpose of illustrating the relative disposition of the two fabrics but the back fabric has not been represented complete in Fig. 1. It has been thought desirable to show the back and front fabrics separately, firstly, for the sake of clearness, and secondly, because

such two fabrics are entirely independent of one another. Similarly in the above description the distance between the adjacent bobbin threads f, f^1 and the distance between adjacent bobbin threads b, b^1 has been referred to as one gait. Actually in the machine one gait represents the distance between an adjacent back and front bobbin but as stated the back and front fabrics are and have been treated in this specification as independent fabrics. Were only a front fabric being produced the loop and cross threads would weave with adjacent bobbin threads $f, b, f^1 b^1, f^2 b^2$, etc. and the above interpretation of "gaits" has therefore been adopted for the sake of clearness.

In other words if only one fabric is being produced all of the bobbin threads will be preferably woven into that fabric and the two gait movements as above described would be two gaits of the machine and not two gaits of the fabric.

For the purpose of joining the front and back fabrics or for forming tubular fabric certain of the pillar threads of each fabric are woven with and certain of the cross threads of each fabric are tied to one and the same bobbin. In other words the front and back fabrics weave or embrace a common bobbin thread. The manner in which the threads are laid to produce this result is represented in Fig. 3.

The loop and cross threads 1, 2 and 3 of the front fabric weave with the front bobbin f and the back bobbin b and the loop and cross threads $1^a, 2^a$ and 3^a of the back thread weave with the back bobbin b and the front bobbin f .

By joining the front and back fabrics at each lateral edge of any convenient width of fabric, tubes may be produced and such tubes may be conveniently joined by lacing threads in a manner well known in the art.

Further if one or two distinct fabrics are produced such fabrics may be produced in any convenient widths and joined by lacing threads.

Figs. 1, 2 and 3 are intended to represent the manner in which the threads are laid for the production of a fabric in accordance with this invention and Fig. 4 is intended to represent the fabric so produced.

From this figure it will be noticed that the loop threads slip over the bobbins on the motions on which such former threads stand and twist with one another intermediate adjacent bobbins. The cross threads and pillar threads remain substantially as laid.

It will be appreciated that by reason of producing a fabric as herein described the loop threads may be carried by one and the same beam seeing that the motions of their respective bars are identical and the tension

of these threads will therefore be equal. Further, the vertical pillars of the fabric 65 impart to it the quality of withstanding longitudinal stress, this feature being particularly desirable in the manufacture of tubular fabrics for mantles and like purposes.

Additionally, as previously stated, each 70 fabric is in effect the combination of two fabrics independent of one another, one of said fabrics or faces consisting of or being presented by the loop threads in combination with the bobbin threads and the other face 75 being presented by the cross threads in combination with the bobbin threads. Accordingly if one of the loop threads breaks the face presented by the cross threads remains intact and vice versa and therefore the fabric 80 in its entirety remains intact.

The feature of producing a fabric with two independent webs as above described is of particular importance in connection with the production of gas and similar mantle 85 fabrics. Not only is the mantle strengthened and the life thereof prolonged but further the gas impinging on such a fabric is directed from the first web to the second web and in thus percolating the fabric more 90 complete combustion of the gas is obtained.

I claim:

1. A fabric presenting two distinct webs adapted for production on twist lace machines comprising a plurality of sets of warp 95 and bobbin threads, one thread of each set of warp threads being twisted always with one and the same bobbin thread, adjacent bobbin threads twisting the one with a warp of one set and the other with the warp of 100 another set, adjacent warp threads twisting with one another intermediate the bobbin threads with which they twist and such threads forming one web of the fabric.

2. A fabric as characterized in the preceding claim and wherein the second web is formed by a set of pillar threads of which there is one to each bobbin thread, each of said pillar threads being twisted with one and the same bobbin thread, and tying each 110 of said bobbin threads with one of the remaining warp threads whereby said last warp threads are caused to lie on adjacent bobbin threads.

3. A process of producing a lace fabric 115 composed of bobbin and warp threads and having a front and a back web, consisting of intertwisting certain of the warp threads each with an individual bobbin thread and simultaneously intertwisting the bobbin 120 threads of the front and back webs with other warp threads.

WILLIAM CHARLES HOPEWELL.
